UNITED STATES PATENT OFFICE.

WILLIAM H. SAUVAGE, OF NEW YORK, N. Y., ASSIGNOR OF FIFTY-ONE TWO-HUNDREDTHS TO GEORGE F. KISSAM, OF NEW YORK, N. Y.

AUTOMATIC AIR-BRAKE MECHANISM FOR RAILROAD-CARS.

SPECIFICATION forming part of Letters Patent No. 769,839, dated September 13, 1904.

Application filed November 3, 1902. Renewed January 19, 1904. Serial No. 189,757. (No model.)

To all whom it may concern:

Be it known that I, WILLIAM H. SAUVAGE, a citizen of the United States of America, and a resident of New York city, county and State 5 of New York, have invented certain new and useful Improvements in Automatic Air-Brake Mechanism for Railroad-Cars, of which the following is a specification.

This invention relates to air-brake systems 10 of the general character of that shown and described in my pending application, Serial No. 189,756, filed January 19, 1904, to which reference may be had for a fuller explanation than is necessary to be given herein.

15 The present improvement is designed more particularly for high-speed trains and for trains operating under conditions which require the application of considerable braking power in the outset and diminished power 20 later.

The particular object in view is to provide 25 for the automatic release of the auxiliary power, which is applied in the outset, and the decrease of the braking power as the speed of the train diminishes.

The nature and object of the invention will be more fully explained hereinafter with reference to the accompanying drawings, in which—

30 Figure 1 is partly a plan view and partly a horizontal section of my improved brake apparatus unattached to a car. Fig. 2 is a detail in side elevation. Fig. 3 is a vertical section of a valve for limiting admission of compressed air to the auxiliary cylinder when auxiliary braking power is not required.

35 The cylinder *a* represents the main brake-cylinder of the ordinary compressed-air brake subject to the control of the usual triple valve (not shown) through the pipe connection *b*.

40 *c* represents the main brake-lever, to which the rod *d* of the main brake-piston is connected, as usual, at *e*. *f* is the usual secondary brake-lever, and *g*, *h*, and *i* indicate connecting-rods of the usual brake apparatus.

45 *j* represents the auxiliary brake-cylinder, and *k* the piston thereof for reinforcing the main brake-cylinder in the latter part of its operation by compressed air admitted there-

to from the main brake-cylinder through the 5° passage *l* when uncovered by the main brake-piston (not shown) in the same manner as in my before-mentioned pending application.

The same automatic attaching and detaching device for connecting and disconnecting 55 the auxiliary piston-rod *m* and the main brake-lever *c*, as shown in the said pending application, is also used herein—viz., the notched end *n* of said rod, cam-slot *o*, and the fixed stud-pin *p*—for deflecting said notched end out of range 60 of the brake-lever when retired by the main brake-piston and returning said notched end into said range when the brake-lever has nearly reached the limit of its forward stroke in the normal application of the brake and just prior 65 to the opening of passage *l* by the main piston to apply the reinforcing effect on the greater leverage after the brake-shoes have been applied to the wheels by the main brake-lever with but slight movement of the aux- 70 illiary brake-piston and corresponding economy of consumption of compressed air. Thus it will be seen that greatly-increased braking power is provided for emergency cases—such, for instance, as a comparatively light passen- 75 ger-train running at high speed or a heavy though slower freight train on a downgrade. Such excessive power is, however, liable to lock the wheels and cause them to slide when, owing to reduction of speed of the train, 80 the wheels have less torque opposing the holding power of the brakes. The primary object of my present invention is therefore to provide simple and effective means for automatically relaxing this excessive power as the 85 train slows and the torque diminishes to avoid the slipping of the wheels, and although various contrivances may be employed for this purpose what I consider at the present time to be the preferable form consists of a slight 90 vent-orifice *q*, affording restricted escape of air from behind the auxiliary piston *k* and gradual reduction of the reinforcing power as the need of such power subsides. This vent may discharge directly into the atmosphere; 95 but as it is the custom for economizing air when in running down long grades with heavy trains the brakes are applied frequently, to

employ retaining-valves for retaining limited pressure behind the piston instead of allowing full discharge I prefer to connect the vent into the usual retaining-valve train-pipe *s* for such retention when required, which is controlled by the usual retaining-valve *t*, which, as is well known, being set in one position by the handle *u*, effects such retention and being set in another position allows free escape when retention is not required.

Another object of my present invention is to control the automatic application of the reinforcing power within the limit of predetermined pressure in the main brake-cylinder below which it is not desirable that the reinforcing power shall take effect, such pressure being sufficient for normal operation of the brakes. For this purpose I provide a check-valve *v* in the passage *l* from the main brake-cylinder to the auxiliary brake-cylinder with means for normally closing said passage and to open it under pressure exceeding the predetermined limit and adapted to be adjusted for varying the opening pressure, such means consisting in this example of the coiled spring *w*, applied to the stem *x* of the valve and compressed between the back of the valve and the adjusting-plug *y* in the head *z* of the valve-case *2*, and a cap *3*, screwing on the upper end of the plug to close the case air-tight and for a check-nut to secure the plug. I also provide a cut-out cock *4* in the passage *l* to cut out the auxiliary brake apparatus altogether when it may be desirable to do so. It will be seen that with such automatic auxiliary brake-controlling valve the engineer may by his brake-operating valve in the cab govern the admission of compressed air into the main brake-cylinder and limit it below the pressure at which the valve *v* is set to open and insure non-action of the reinforcing power when not wanted and when emergency requires he may by larger admission so increase the pressure in the main cylinder as to open valve *v* and set the reinforcing power in action whenever required.

What I claim as my invention is—

1. In an air-brake, the combination with the brake-lever and the main brake cylinder and piston, of an auxiliary brake cylinder and piston, means for reinforcing the main brake cylinder and piston in the latter part of their stroke by the auxiliary cylinder and piston, and means for automatic gradual reduction of

the power of the auxiliary cylinder and piston as the speed of the train diminishes.

2. In an air-brake, the combination with the brake-lever and the main brake cylinder and piston, of an auxiliary brake cylinder and piston, means for reinforcing the main brake cylinder and piston in the latter part of their stroke by compressed air admitted into the auxiliary cylinder from the main cylinder, and means for automatic gradual reduction of the power of the auxiliary cylinder and piston as the speed of the train diminishes by restricted release of compressed air from the auxiliary cylinder.

3. In an air-brake, the combination with the brake-lever and the main brake cylinder and piston, of an auxiliary brake cylinder and piston, means for reinforcing the main brake cylinder and piston in the latter part of their stroke by compressed air admitted into the auxiliary cylinder from the main cylinder by the main piston, and means for gaging the pressure for such admission:

4. In an air-brake, the combination with the brake-lever and the main brake cylinder and piston, of the auxiliary brake cylinder and piston, means for reinforcing the main brake cylinder and piston in the latter part of their stroke by compressed air admitted into the auxiliary cylinder from the main cylinder by the main piston, and means for gaging the pressure for such admission consisting of the adjustable check-valve in the passage from the main brake-cylinder to the auxiliary brake-cylinder.

5. In an air-brake, the combination with the brake-lever and the main brake cylinder and piston, of an auxiliary brake cylinder and piston, means for reinforcing the main brake-cylinder in the latter part of their stroke by compressed air admitted into the auxiliary cylinder from the main cylinder, means for automatic gradual reduction of the power of the auxiliary cylinder and piston as the speed of the train diminishes and means for gaging the pressure for admission of air from the main brake-cylinder to the auxiliary brake-cylinder.

Signed at New York this 1st day of November, 1902.

WILLIAM H. SAUVAGE.
